UNITED STATES PATENT OFFICE.

HIRAM G. SEDGWICK, OF MILL VALLEY, CALIFORNIA.

ELECTRICAL TRAIN-STOP.

No. 852,632.

Specification of Letters Patent.

Patented May 7, 1907.

Application filed June 14, 1906. Serial No. 321,762.

To all whom it may concern:

Be it known that I, HIRAM G. SEDGWICK, a citizen of the United States of America, and a resident of Mill Valley, county of Marin, State of California, have invented certain new and useful Improvements in Electrical Train-Stops, of which the following is a full and clear specification, reference being had to the accompanying drawing, in which—

10 Figure 1 is a diagram showing one section or block of a single track roadway; and Fig. 2 a side elevation showing the stopping magnet and the electrically-controlled train-stopping circuit on the locomotive or other vehicle of the train.

15 The object of this invention is to provide an extremely simple block system for preventing collisions, means being provided whereby each train as it proceeds preëmpts a block or section of the roadway, preventing any train coming from either direction from entering the block until it is free of trains, the means for preventing trains from entering the block while thus preëmpted being entirely automatic and independent of all signals and the actions of the train-crews, as more fully hereinafter set forth.

20 Referring to the drawings annexed by reference-characters, *a* designates the main or block sections of the rails of each of which is bonded in the usual manner, and *b* designates short rail sections one of which is placed between the adjacent ends of each pair of block sections and is insulated therefrom. Adjacent to each short rail section, at each side of the track, is a pair of contacts *c* suitably insulated from each other.

25 Each pair of contacts is included in a circuit *d*, one end of this circuit being connected to the block rails and the other to the adjacent short rails, so that each circuit will be open at three points, namely between the contacts, between the short rail sections, and also between the rails of the block. The contacts on the left hand side of the roadbed are connected with the adjacent ends of the rails of one of the blocks and the circuit of each right hand pair of contacts is connected to the adjacent ends of the other block, so that the latter contacts are adapted to co-operate with trains going toward the right while the other contacts are adapted to co-operate with trains going toward the left.

30 Any suitable brake-applying mechanism may be used on the locomotive. In Fig. 2 I show one arrangement for operating the

brake-magnet *d'*, one terminal of this magnet being connected with a pair of stationary contacts *e* secured to the segment of the usual reverse lever *f* of the locomotive. The other terminal of the magnet is connected to two brushes *g*, *g'*, arranged upon opposite sides of the locomotive in the usual manner. The other brushes *g*, *g'*, are connected through a battery *h* to a contact *i* on the reverse lever. By this arrangement it will be observed that when the reverse lever *f* is thrown forward to drive the locomotive forwardly, the contact *i* will come into contact with the forward one of the contacts *e* thereby bringing into the circuit the brushes *g'* which will be on the right hand side of the locomotive and at the same time cut out the brushes *g* which will be located on the left hand side of the locomotive. When the reverse lever is adjusted backwardly the other pair of brushes *g* will be in circuit with the magnet and the battery, thereby rendering the brushes *g'* inactive. It will be observed, therefore, that by the act of reversing the direction of movement of the locomotive the proper pair of brushes will be brought into requisition, the devices for accomplishing this being exceedingly simple as is obvious. In my former application serially numbered 288,914, filed November 24, 1905, I have shown another mechanism for thus automatically cutting out the brushes that are to be inactive.

35 It will be observed that in this system when a train is on one of the blocks no other train can enter that block from either end as when it approaches the block it will be stopped at the short rail section. The train in the block through its wheels and axles completes part of the circuit while the oncoming train completes the other two breaks in the circuit by means of its wheels and axles and its brushes.

40 It will be obvious that this invention is not confined to the specific details of construction shown and described.

45 What I claim and desire to secure by Letters Patent is:—

1. In a system of the character set forth, a series of block rails suitably bonded, a short rail section between each pair of block rails and insulated from the block rails, a pair of contacts at each side of the track adjacent the short rail sections, and a partial circuit connected to each pair of contacts and to the short rail sections and the main block rails, so that each circuit will be open at three

points, the contacts at one side being connected to one pair of block rails and the contacts at the other side being connected to the rails of the next succeeding block.

- 5 2. In a train-stopping apparatus for use on a locomotive, a brake magnet, a pair of brushes at each side of the locomotive, two partial circuits including the brushes and the magnet and a battery, a pair of stationary contacts connected to both circuits, and a movable contact carried by the reverse lever of the locomotive, for the purpose set forth.
- 10 3. In a system of the type set forth, a series of main block rails suitably bonded, a series of short rail sections interposed between and insulated from said main sections, a pair of contacts adjacent to each short rail section, and a partial circuit for each pair of contacts, said circuit including the contacts, 15 the rails of the short section, and the rails of the adjacent block section whereby the cir-

cuit will be open at three points, substantially as and for the purpose set forth.

- 20 4. In a system of the character set forth, a series of block rails and intermediate insulated short rail sections, a pair of contacts adjacent to the right hand short rail section, one of these contacts being electrically connected to the adjacent short rail and the other being connected to the adjacent end of the right hand rail of the block just ahead, and a conductor electrically connecting the opposite short rail section to the left hand rail of the block just ahead, for the purpose set forth.

In testimony whereof I hereunto affix my signature in the presence of two witnesses this 7th day of April 1906.

HIRAM G. SEDGWICK.
